(57) **CLAIM**

The ornamental design for a strap for hand-held electronic game machine, as shown and described.

DESCRIPTION

FIG. 1 is a front view of a strap for hand-held electronic game machine showing our new design, a rear view being a mirror image thereof;

FIG. 2 is a top plan view thereof;

FIG. 3 is a bottom plan view thereof;

FIG. 4 is a left side view thereof;

FIG. 5 is a right side view thereof;

FIG. 6 is a reference front view showing a state that an adjuster ring is moved from a state of FIG. 1;

FIG. 7 is a reference perspective view showing the strap alone;

FIG. 8 is another reference perspective view showing an aspect that the strap is attached to a hand-held electronic game machine; and,

FIG. 9 is another reference perspective view showing the strap attached to a hand-held electronic game machine.

The broken line showing of environment in the drawings is for illustrative purposes only and forms no part of the claimed design.
